[57] CLAIM

The ornamental design for a universal serial buss, as shown and described.

DESCRIPTION

FIG. 1 is a perspective view taken from the front, bottom, and right side of universal serial buss showing my new design;

FIG. 2 is a perspective view taken from the front, top, and right side thereof;

FIG. 3 is a front elevational view thereof;

FIG. 4 is a back elevational view thereof;

FIG. 5 is a right side elevational view thereof, the left side being a mirror image;

FIG. 6 is a bottom plan view thereof; and,

FIG. 7 is a top plan view thereof.

The broken line showing in FIGS. 1, 2 and 3 are included to illustrate environmental features only and form no part of the claimed design.
